[57] CLAIM

The ornamental design for a medication dispenser, as shown and described.

DESCRIPTION

FIG. 1 is a front elevational view of a medication dispensing showing my new design.

FIG. 2 is a right-hand side elevational view thereof.

FIG. 3 is a top plan view thereof.

FIG. 4 is a rear elevational view thereof.

FIG. 5 is a bottom plan view thereof.

The appearance of the left-hand side is a mirror image of that shown in FIG. 2 for the right-hand side.
